CLAIM

The ornamental design for a direct delivery unit for application of dental materials or the like, as shown and described.

DESCRIPTION

FIG. 1 is a perspective view of a direct delivery unit for application of dental materials or the like showing our new design;

FIG. 2 is a front end elevational view thereof;

FIG. 3 is a rear end elevational view thereof;

FIG. 4 is a top plan view thereof;

FIG. 5 is a right side elevational view thereof, the left side being a mirror image;

FIG. 6 is a bottom plan view thereof; and,

FIG. 7 is a perspective view thereof, with the broken-line showing of the unit dose cartridge being for illustrative purposes only and forming no part of the claimed design.
